(57) **CLAIM**

The ornamental design for a decorative panel for a welding cart, as shown and described.

DESCRIPTION

FIG. 1 is a top perspective view of a decorative panel for a welding cart showing my new design; and, FIG. 2 is a right elevational view thereof, the left elevational view being a mirror image thereof.

The broken lines shown in the figures are included for the purpose of illustrating environment and form no part of the claimed design.
